UNITED STATES PATENT OFFICE.

FRANK A. DEGNER, OF SALEM, SOUTH DAKOTA.

LUGGAGE CARRIER.

Application filed April 24, 1923. Serial No. 634,308.

To all whom it may concern:

Be it known that I, FRANK A. DEGNER, a citizen of the United States, residing at Salem, in the county of McCook and State of South Dakota, have invented certain new and useful Improvements in Luggage Carriers; and I do hereby declare the following to be a full, clear, and exact description of the invention, such as will enable others skilled in the art to which it appertains to make and use the same.

The present invention relates to luggage carriers or racks for vehicles, and aims to provide a novel and improved attachment for the running board of an automobile or other similar support, for holding a crate, trunk, box or other object on the running board or support without danger of falling therefrom.

It is also an object of the invention to provide such a luggage carrier which is extremely simple and inexpensive in construction, and which can be readily applied to the running board or support.

Another object is to render the device adjustable for objects of different sizes.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

Figure 1 is a plan view of the luggage carrier.

Fig. 2 is an end view thereof.

Fig. 3 is a side elevation thereof, portions being shown in section.

The carrier or rack is composed entirely of bars or strips of metal and bolts or other securing elements, so that it can be made easily and cheaply. The carrier comprises two or more right-angled or L-shaped bars 7 having the feet 8 to extend transversely over and seat on the running board 9 or other support, and said bars have the uprights 10 which are spaced from the outer edge of the running board, as seen in Figs. 1 and 2. Two or more horizontal bars or rails 11 extend across and are secured to the uprights 10 by means of bolts 12 or other securing elements, to constitute, with the uprights 10, an outer or front wall for holding

a crate, box, trunk or other object on the running board. The terminals of the bars 11 are bent at right angles to project inwardly, as at 13, to provide the ends of the 60 rack or carrier for preventing the crate or other object from moving end-wise out of the carrier or rack.

In order to secure the bars 7 on the running board or support, clamping bars 14 65 are disposed under the feet 8 of the bars 7, and their outer end portions are widened, as at 18, and secured to the feet 8 near the uprights 10, by the U-bolts 15 or similar clamping elements, with the inner end portions of the bars 14 extending under the running board and bearing upwardly against the under surface of said board. The bars 14 have depending offsets 16 to engage under and around the depending flange 17 at the 75 outer edge of the running board, thereby preventing the carrier or rack from slipping side-wise. The outward tilting movement of the carrier or rack is resisted by the bars 14 which bear upwardly against 80 the lower surface of the running board, and the object seating on the feet 8 will assist in holding the carrier in its upright position, so that there will not be much outward pressure on the outer or front wall of the carrier. The feet 8 are arranged to seat on the running board while the clamping bars 14 are formed to engage under the running board, thereby securing the carrier or rack 85 to the running board without the necessity 90 for engaging securing elements through the running board itself, and the securing elements or bolts 15 as used are spaced outwardly beyond the outer edge of the running board so as to be readily accessible in applying and removing the device.

The carrier is rendered adjustable for objects of different sizes, by the sliding connection between the bars 7 and 14. Thus, the 100 U-bolts or clips 15 straddle the feet or portions 8 of the bars 7 and have their terminals engaging downwardly through apertures in the widened portions 18 of the bars 14, with nuts 19 threaded on the terminals 105 of said bolts or clips and seating upwardly against said portions 18, whereby to clamp the feet 8 on the portions 18 when the bolts are tightened. By loosening the nuts 19, the bars 7 can be adjusted transversely of the running board or support to make the luggage compartment or space wider or narrower, it being noted that the bars 14 retain 110

their position by being engaged with the flange 17 of the running board or support. The outer terminal portions of the bars 14 are substantially horizontal and flush with the upper surface of the running board 9, and the inner terminal portions of said bars are also substantially horizontal but are offset downwardly below the plane of the outer end portions so as to extend below the running board. Thus, the feet 8 bear snugly on the running board and outer terminal portions of the bars 14, and said feet being secured on said portions of the bars will render the bars 14 effective to prevent the carrier from tilting outwardly.

The carrier can be used by farmers, for holding a crate of eggs, vegetables, fruit, or the like, on the running board, and can be used by tourists for holding baggage or luggage.

Having thus described the invention, what is claimed as new is:

1. A luggage carrier comprising a wall having a foot to bear on a running board, a clamping bar under said foot, one terminal of said bar being arranged to extend under and bear upwardly against said board, the other terminal portion of said bar being substantially flush with said board beyond the edge thereof, and means for clamping said foot on the lastnamed terminal portion of said bar.

2. A luggage carrier comprising a wall having a foot to bear on a running board, a clamping bar under said foot and having substantially horizontal terminal portions and a depending offset between said portions to engage under a depending flange at the edge of said board, one terminal portion being arranged to fit under and bear upwardly against said board, the other terminal portion being substantially flush with said board beyond said flange, and means for securing said foot on the lastnamed terminal portion of said bar.

3. A luggage carrier comprising a wall having feet to bear against a running board or other support, clamping bars to bear against the support opposite to said feet, and securing means connecting said bars and feet

to clamp them together against the support and permitting, when loosened, the longitudinal sliding movement of the feet relatively to said bars.

4. A luggage carrier including an angle bar having an upright and a foot to bear against the running board or other support, a clamping bar to bear against said support opposite to said foot, and securing means for fastening said clamping bar and foot together to clamp them against the support, and to permit, when loosened, the longitudinal sliding movement of the foot relatively to the clamping bar.

5. A luggage carrier comprising portions to be clamped to a running board or similar support, and means for slidably connecting said portions and clamping them together beyond said running board or support, whereby one of said portions can be adjusted to change the size of the carrier.

6. A luggage carrier comprising portions to extend over and under a running board or similar support, the lower portion being formed to engage the running board or support and to retain itself in position, and means for slidably connecting said portions and clamping them together beyond the running board or support, so that the upper portion can be adjusted relatively to the board or support for changing the size of the carrier.

7. A luggage carrier comprising a wall having feet extending therefrom to bear on a running board or similar support, clamping bars under said feet to extend under the support, and means for securing said bars upwardly against said feet beyond said support to clamp the bars upwardly against the support, said means, when loosened, permitting the feet to be slid longitudinally relatively to said bars.

In testimony whereof I have signed my name to this specification in the presence of two subscribing witnesses.

FRANK A. DEGNER.
